UNITED STATES PATENT OFFICE

159,990

ARTIFICIAL LURE

Lewis J. Kalvig, Hackensack, Minn.

Application March 18, 1949, Serial No. 1,474

Term of patent 14 years

(Cl. D31—4)

To all whom it may concern:

Be it known that I, Lewis J. Kalvig, a citizen of the United States of America, residing at Hackensack, in the county of Cass and the State of Minnesota, have invented a new, original, and ornamental Design for an Artificial Lure, of which the following is a specification, reference being had to the accompanying drawing, forming a part thereof.

Figure 1 is a side elevational view of an artificial lure, and

Figure 2 is a plan view of the same showing my new design.

I claim:

The ornamental design for an artificial lure, as shown.

LEWIS J. KALVIG.
